O. JOHNSON

BRAKE BEAM SAFETY HANGER

Filed July 16, 1923

UNITED STATES PATENT OFFICE.

OLOF JOHNSON, OF HUDSON, WISCONSIN, ASSIGNOR OF ONE-THIRD TO WILLIAM H. THORN AND ONE-THIRD TO OSCAR SOLHEIM, BOTH OF HUDSON, WISCONSIN.

BRAKE-BEAM SAFETY HANGER.

Application filed July 16, 1923. Serial No. 651,921

To all whom it may concern:

Be it known that I, OLOF JOHNSON, a citizen of the United States, residing in Hudson, in the county of St. Croix and State of Wisconsin, have invented a new and useful Brake-Beam Safety Hanger, of which the following is a specification.

My invention relates to improvements in brake beam safety hangers for railway 10 freight cars.

One object of the invention is to provide a simple and durable hanger of the present nature adapted to prevent the falling of a brake beam to the road bed and designed to 15 be quickly and easily detached from its supporting truck member to permit of the ready removal of the brake beam for repair or other purposes.

Another object is to supply a readily 20 detachable safety hanger of this kind, embodying self-contained yielding means operating to secure the hanger in place upon its support and also to prevent vibration and rattling thereof.

25 A further object is to provide a hanger of the instant nature, the parts of which normally remain assembled, whereby the labor of assembling during application and disassembling during removal is avoided and 30 the loss or misplacement of parts prevented.

With the foregoing and other objects in view, which will appear in the following description, the invention resides in the novel combination and arrangement of parts and 35 in the details of construction hereinafter described and claimed.

40 Safety hangers in the form of loops or brackets bolted or riveted to parts of car trucks have been used, but difficulties have been met in applying, maintaining the same in place and removing them. Many of these difficulties are overcome in my improved device which provides, among other things, for 45 convenient application and removal in assembled form, for secure attachment without vibration, for assurance against accidental unthreading of securing nuts or the wearing and shearing of retaining rivets and for the avoidance of damage to parts attended upon removal.

45 In the drawings, Fig. 1 is a side elevation of a device embodying my invention, the same being illustrated as applied to the spring plank of a truck; Fig. 2 is a similar 50 view, a brake beam and other truck parts

being also shown; Fig. 3 is a fragmentary plan view of the device, a portion of a supporting spring plank being illustrated; Fig. 4 is a sectional view taken as on the line 4-4 of Fig. 3; Fig. 5 is a sectional view taken as 60 on the line 5-5 of Fig. 4 and Figs. 6 and 7 are elevational views illustrating an alternate form of a bracket member and mounting therefor.

My improved safety hangers are used in 65 pairs, the same being applied to the spring plank of a truck and spaced apart so that the end of a brake beam accidentally released will be caught and held against falling to the road bed.

70 The hanger includes a bracket member A and a fender member B, as will be observed from the drawings, wherein similar reference characters have been used throughout the several views to indicate similar parts. 75 The bracket member A comprises a shank 10 formed with a saddle block 11 at its head and with an arm 12 reaching back from the base thereof. The saddle block 11 has a flange receiving recess 13 in its lower side. 80 With said block saddled on the upper edge of a flange 14 of a spring plank C (Fig. 4), the shank 10 lies against the inner side of said flange 14. A pin 15 depending from the end of the arm 12 is provided to register with an aperture 16 in a spring plank web 17 and hold the bracket member A against sliding longitudinally on the spring plank C. The fender member B is hinged to the bracket member A and comprises a 85 body 18 and angular fender arm 19 integral therewith.

90 The body 18 includes side pieces 18^a, which terminate at the top thereof in ears 20, said pieces being continued along the under side 95 of the fender arm 19 to form strengthening ribs 19^a. The bracket and fender members A and B constitute male and female hinge members, a pintle 21 reaching through the ears 20 and saddle block 11 supplying the 100 connecting pivot. With the bracket member A riding the flange 14 as shown in Fig. 4 and with the fender member B folded as far as possible on said bracket member, flange 105 engaging portions 18^b on the side pieces 18^a of the body 18 are brought against the outer side of the flange 14. Latch lugs 22, embodied in said side pieces 18^a catch beneath the underside of the spring plank C in such 110 folded relation of said bracket and fender

members A and B and lock the former on the spring plank. I interpose a keeper 23 between the two hinged members A and B to yieldingly hold the latter against the spring 6 plank flange 14 with the latch lugs 22 in locking position therebeneath. This keeper 23 is a spring leaf, the lower end thereof being seated in a socket 24 formed at the lower end of the body 18 by the angular 10 web 25 spanning the space between the side pieces 18^a of said body. Shoulders 26 on the perimeter of the saddle block 11 at the forward side thereof supply abutments for the upper end of the spring leaf 23, the 15 same being considerably offset from the axis of the pintle 21. With the spring leaf 23 bearing beneath the shoulders 26 at its upper end and against the bottom of the socket 24 at its lower end, it will be understood that 20 the fender member B is held by said spring against swinging in a direction to carry the latch lugs 22 from locking position beneath the spring plank C. The socket 24 is so arranged and the spring leaf 23 of such 25 length that the upper end of the leaf, is forced against the saddle block 11 beneath the shoulders 26. This arrangement bows the spring leaf (Fig. 4), the resiliency thereof tending to yieldingly press the body 18 30 of the fender member B against the face of the spring plank flange 14. The fender member B being thus held by said spring leaf 23 against swinging from locked relation and being yieldingly pressed against the flange 14, it will be understood that the 35 device will normally remain firmly fixed in place.

In applying the hanger, the fender member B is swung away from the bracket member A as shown in dotted lines Fig. 4, to 40 permit the straddling of the flange 14 of a spring plank. The pin 15 is guided into an aperture 16 bored in the web 17 to receive it and the saddle block 11 is seated on the upper edge of said flange. The fender member B is then further folded on the bracket member A to carry the latch lugs 22 beneath the spring plank (solid lines Fig. 4) and the surfaces 18^b against the face of 45 the flange 14. In this position of the fender member B, the upper end of the spring leaf 23 is caught beneath the shoulders 26 on the saddle block 11.

In removing the hanger, a chisel or other 50 instrument is inserted in the space 27 (Fig. 3) between the spring leaf 23 and saddle block 11. By prying outwardly against said leaf, the upper end thereof is sprung from locking position beneath the shoulders 26, whereupon the fender member B may be 55 swung to position (dotted lines Fig. 4), freeing the latch lugs 22 from the spring plank. Having unlocked the device from the spring plank, as just described, the 60 bracket member A is easily lifted sufficiently

to unseat the saddle member 11 from the flange 14 and remove the pin 15 from its receiving aperture 16, whereupon the structure is entirely freed from the spring plank. Should it be desired to remove the spring 70 leaf 23 for repair or replacement, a tool is inserted in a kerf 25^a in the bottom of the web 25 and said leaf dislodged by driving the tool upward in said kerf and against the bottom of said spring leaf. Having no 75 normally separable parts and only requiring an aperture in the plank that is readily formed with an ordinary drill, my device may be quickly and easily applied in assembled form and likewise removed. 80

My alternate form (Figs. 6 and 7) meets a condition wherein there is insufficient room on the inside of a spring plank flange 14 for a bracket member A. The only change 85 over the form shown in Figs. 1-5 is in said bracket member A. In said alternate form, the arm 12 is omitted, the shank 10 being inserted between the spring plank and a supplementary flange 14^a secured to the face 90 of the flange 14 of said spring plank. The saddle member 11 rides the upper edge of the supplementary flange 14^a and the latch lugs 22 of the fender member B are caught beneath the lower edge of said flange in the 95 manner explained in connection with the form shown in Figs. 1-5.

Changes in the specific form of my invention, as herein disclosed, may be made within the scope of what is claimed without departing from the spirit of my invention. 100

Having described my invention, what I claim as new and desire to protect by Letters Patent is:

1. A brake beam safety hanger including bracket and fender members, the former comprising a shank, a saddle block at the top and an arm at the base thereof, said block being adapted to ride the upper edge of a spring plank flange, the arm being formed with a depending pin to register 105 with an aperture in the web of the spring plank, the fender member comprising a body and an angular fender arm integral therewith, said body having ears at the head thereof and latch lugs near its lower end, the latter serving to catch beneath the 110 spring plank, a pintle reaching through said ears and saddle block and hingedly joining said members, a holder near the lower end of said body, a spring leaf seated at its lower end in said holder and bowed by engagement of its upper end with the saddle block, the tension of the bowed spring leaf serving to yieldingly hold the fender member 115 against the flange with the latch lugs beneath said plank, and shoulders on the saddle block forming abutments for the upper end of the spring leaf and adapted to normally hold said spring leaf in said holder. 120
2. A brake beam safety hanger including 125

- bracket and fender members, the former comprising a saddle block adapted to ride the upper edge of a spring plank flange, the fender member comprising a body and an angular fender arm integral therewith, said body having an ear at the head thereof and a latch lug near its lower end, the latter serving to catch beneath the spring plank, a pintle reaching through said ear and saddle block and hingedly joining the fender member therewith, and a spring leaf caught at its lower end near the lower end of said body, said spring leaf being bowed by engagement of its upper end with the saddle block, the tension of said spring serving to yieldingly hold the fender member against the flange with the latch lugs beneath the spring plank.
3. A brake beam safety hanger including bracket and fender members, the former comprising a saddle block adapted to ride the upper edge of a spring plank flange, the fender member comprising a body and an angular fender arm integral therewith, said body having an ear at the head thereof and a latch lug near its lower end, the latter serving to catch beneath the spring plank, a pintle reaching through said ear and saddle block and hingedly joining the fender member therewith, a rest on the body, a shoulder on the saddle block offset from the axis of the pintle, a keeper seated at its lower end on said rest and engaged beneath said shoulder at its upper end, said keeper serving to hold the fender member against swinging on the saddle block in a direction to carry the latch lugs from locking position beneath the spring plank.
4. The combination with a supporting frame member, of a hinge member riding the same, a second hinge member pivoted to the said first hinge member, a latch lug and a fender arm on said second member, said lug being arranged to catch beneath the frame member and lock said members in place thereon, and a keeper co-acting with the hinge members to secure said second member against swinging from locking position.
5. The combination with a supporting frame member, of a hinge member riding the same, a second hinge member pivoted to the said first hinge member, a latch lug and a fender arm on said second member, said lug being arranged to catch beneath the frame member and lock said members in place thereon, and a resilient keeper co-acting with the hinge members to yieldingly press said second member against the frame member in locking position.
6. In a hanger, a bracket member adapted to be saddled on a supporting flange, a fender member hinged on said bracket member and formed with a catch to engage the underside of said flange, and a spring leaf co-operating with said members to yieldingly hold the same against relative pivoting movement and thereby normally lock the hanger on the flange.
7. A brake beam safety hanger comprising a hinged structure adapted, when folded together, to straddle a supporting flange, said structure including a bracket member, a fender member pivoted thereto, said fender member having a catch thereon for engagement with the underside of the flange, and means for holding said members in folded relation.
8. A brake beam safety hanger comprising two hinged members adapted to fold over a supporting flange and interlockingly embrace the same, and means for yieldingly holding said members in folded flange embracing relation.
9. In a device of the class described, a pair of hinged members having means for opposed engagement with a spring plank, and a keeper normally operating to prevent the swinging of one member on the other in a direction to free the device from the spring plank.

In testimony whereof, I have signed my name to this specification.

OLOF JOHNSON.
